CLAIM

The ornamental design for a clasp for purses and handbags as shown and described.

DESCRIPTION

FIG. 1 is a perspective view of my new design for a clasp for purses and handbags.

FIG. 2 is a front view thereof.

FIG. 3 is a back view thereof.

FIG. 4 is a top view thereof.

FIG. 5 is a bottom view thereof.

FIG. 6 is a right side view thereof; and,

FIG. 7 is a left side view thereof.

The broken lines and lightened portions within, shown in FIGS. 3 and 4, illustrate portions of the clasp for purses and handbags that form no part of the claimed design.

1 Claim, 7 Drawing Sheets
